UNITED STATES PATENT OFFICE.

JULIUS H. LUTZ, OF NEW YORK, N. Y., ASSIGNEE OF ONE-FOURTH TO HARRY RADZINSKY, OF NEW YORK, N. Y.

ELECTRICAL CONNECTION CLIP.

Application filed September 26, 1926. Serial No. 187,658.

This invention relates to a clip or attaching device for electrical wiring, and particularly wiring of the character employed in radio sets and radio work generally, and has for its object to provide a connection clip which will firmly and securely grip the wiring or buss bar without employing the use of solder, and will thus establish a positive and secure electrical connection between the parts of the instrument and the connecting wires.

It is well known that where solder is employed in joining electrical wiring to binding posts or to the ordinary flat type of "soldering lug" used on said posts, a soldering flux must be used. If an insufficient amount of flux is used, a poor joint is produced. There is thus the tendency among amateur workmen to use more flux than is required, with the result that it spreads into the electrical instruments, and unless considerable skill is possessed by the workman, inefficient electrical connections between the instruments employed in a radio set or other electrical device, result.

The main object, therefore, of my invention, is to provide a connection clip for use on the binding posts of electrical instruments, which will be so constructed that a soldered joint between it and the wiring, is obviated. My improved connection clip very firmly grips and holds the wiring, with the result that a clean, firm and efficient electrical contact is established between it and the wire which it holds.

With these objects, and such other objects as may hereinafter appear, in view, I have devised the particular arrangement of parts hereinafter set forth and more particularly pointed out in the claims appended hereto.

Reference is to be had to the accompanying drawing, forming a part hereof, in which

Figure 1 is a side elevation, partly in section, of my improved clip as applied to a binding post, before the nut on the binding post is threaded down;

Figure 2 is a side elevation of the same, showing the binding post nut threaded down and the clip firmly gripping a wire or buss bar;

Figure 3 is a sectional view on the line 3—3 of Figure 1, looking in the direction of the arrows;

Figure 4 is a sectional view on the line 4—4 of Figure 2, looking in the direction of the arrows;

Figure 5 is a side elevation, partly in section, of a modified form of clip;

Figure 6 is a plan view of the clip shown in Figure 5;

Figure 7 is another modified form of clip;

Figure 8 is a side elevation showing the clip disclosed in Figure 7 as it appears when applied to a binding post on an instrument;

Figure 9 is a sectional view on the line 9—9 of Figure 8, looking in the direction of the arrows;

Figure 10 is a side elevation, partly in section, of another modified form of clip, in which the wiring or buss bar is inserted from the front of the clip; and

Figure 11 is a sectional view on the line 11—11 of Figure 10, looking in the direction of the arrow.

Throughout the various views of the drawing, similar reference characters designate similar parts.

In the embodiment of my invention as disclosed in Figures 1 to 4 inclusive of the drawing, I have shown my improved clip as being formed from a single elongated strip of flat or sheet metal. The metal employed should possess considerable resiliency in order to function properly, yet should also be sufficiently rigid to afford a forcible and firm gripping pressure upon the wire or buss bar which it engages.

The strip shown, is folded upon itself, as at 1, so that it is divided into a pair of arms 2 and 3, which normally tend to spring apart for some distance by reason of the resiliency in the metal. The arms 2 and 3 are provided with enlarged free ends as at 4 and 5, and openings 6 are therein provided to permit the passage of a binding post 7 or other similar projecting part on an electrical instrument, a part of which is indicated at 8.

The arm 3 is provided with a pair of laterally extending wings 9, which are formed on the longitudinal side edges of the arm at a position adjacent to the bend or fold 1 in the strip. These wings 9 are folded so that they lie at substantially right angles to the plane of the arms 2 and 3 and they thus project away from the arm 3 and toward the arm 2.

From the foregoing it will be readily apparent how my improved clip, just above described, operates. It is shown in Figure 1 in dotted lines in the form in which it appears when it is first slipped over the binding post 7. A wire or buss bar 10 is inserted between the inner face of the fold 1 of the clip and the side edges 11 of the wings 110

9, said side edges 11 being those which are located nearest to the fold 1. The binding post nut 12 is then threaded down firmly, with the result that the wings 9 are inclined forwardly, and they firmly grip the wire 10 between their forward edges 11 and the inner face of the strip at the fold 1. The grip exerted on the wire is a firm and strong one regardless of whether the wire is of the type 10 known as "buss bar" or whether it is of the stranded type, and a clean, strong and effective mechanical and electrical joint is the result.

In Figures 5 and 6 is shown a modification 15 of my improved clip, wherein a single gripping wing or lug 13 is utilized to hold the wire 10 between its forward edge 14 and the fold 1 in the strip. This wing 13 is struck out of the body of the arm 3 and is 20 bent toward the arm 2 which is provided with an aperture 15 through which the wing 13 may project when the arms 2 and 3 are compressed toward one another.

In the modification of my invention disclosed 25 in Figures 7 to 9 inclusive, the clip is in the main, similar to that disclosed in Figures 1 to 4 inclusive, except that its gripping members or wings, which are shown at 17 and 18, are made wider than those disclosed at 9 30 in Figures 1 to 4, so that they grip the wire or buss bar 10 between their notched lower edges 19 and the upper face 20 of the arm 2. Figure 8 clearly discloses the positions of the various parts of the clip when the same is in 35 its final position. A feature of the clip disclosed at Figures 7, 8 and 9 is that it may confine and hold at least two wires. One of the wires so held and confined may be gripped as shown, that is, between the notched or recessed ends 19 of the wings 17 and the face 40 of the part 20, and a second wire may be simultaneously gripped and held between the front edges of said wings and the looped or folded part 1 as is done in the embodiment 45 of my invention disclosed in Figures 1 to 4 inclusive.

In the modification of my device disclosed in Figures 10 and 11, the clip is provided with an aperture 21, located on the line of

the fold, and a wire or buss bar 10 may be 50 inserted from the front of the clip through the aperture 21 so that it passes between struck-up prongs 22 and 23. The prongs 22 are shown as being struck from the body of the arm 2 and the prong 23 is formed from 55 the body of the arm 3. These prongs 22 and 23 have their lower edges notched as at 24, so that when the arms 2 and 3 are compressed towards one another by the action of the nut 12 on the binding post, the lower edges 24 on 60 the prongs will firmly grip and hold the buss bar or wire.

From the foregoing it will be apparent that I have produced an electrical connection clip of extreme simplicity of construction, yet 65 one which will be highly efficient in operation. A feature of importance is that the nature of the clip enables it to act as a "lock washer" for the binding post nut, for the normal tendency of the arms 2 and 3 to spring apart 70 causes them to exert spring pressure against the nut tending to cause it to remain firmly in position under all conditions of use.

Having described several embodiments of my invention, it is obvious that the same is 75 not to be restricted thereto, but is broad enough to cover all structures coming within the scope of the annexed claims.

What I claim is:—

1. An article of the class described comprising a strip folded upon itself, wings bent from said strip and positioned no further away from the fold than the normal distance between the folded parts of the strip, said wings being adapted to grip a wire between 85 one of their edges and fold in the said strip.

2. An article of the class described comprising a strip folded upon itself to form a pair of flexible arms capable of movement toward one another, a wing bent from one of 90 said arms and located sufficiently close to the fold in the strip to cause a cylindrical wire to be firmly gripped between that edge of the wing which is located nearest to the fold and the fold, when the arms are compressed 95 toward one another.

JULIUS H. LUTZ.
